(57) **CLAIM**

The ornamental design for an electrical connector, as shown and described.

DESCRIPTION

FIG. 1 is a front elevational view of an electrical connector in accordance with my new design;

FIG. 2 is a top plan view thereof;

FIG. 3 is a rear elevational view thereof;

FIG. 4 is a bottom plan view thereof;

FIG. 5 is a right side elevational view thereof;

FIG. 6 is a left side elevational view thereof;

FIG. 7 is a right side elevational view thereof with the contact parts thereof pushed slightly into the body;

FIG. 8 is bottom plan view thereof with the contact parts slightly pushed into the body;

FIG. 9 is a cross-sectional view taken along the line 9—9 in FIG. 1;

FIG. 10 is a cross-sectional view taken along the line 10—10 in FIG. 1; and,

FIG. 11 is a perspective view thereof.
